UNITED STATES PATENT OFFICE

2,039,937

OIL COMBUSTION APPARATUS

Oscar C. Schroeder, Chicago, Ill.

Application August 2, 1933, Serial No. 683,372

17 Claims. (Cl. 158—4)

One of my objects is to provide in oil combustion apparatus of the type in which the combustion of the oil delivered from the center of the hearth takes place generally in the form of a ring at the outer peripheral portion of the hearth, improvements to the end that the apparatus may be started quickly into operation, complete combustion of the fuel will be effected; and maximum efficiency will be obtained; and other objects, as will be manifest from the following description.

Referring to the accompanying drawings:

Figure 1 is a view in elevation of the lower portion of a furnace embodying my invention and comprising, as an element thereof, an oil burner assembly, certain portions of the structure shown being represented in sectional elevation.

Figure 2 is a plan view of a ring associated with the hearth, together with the clip devices for holding it in position.

Figure 3 is a broken perspective view of a portion of the ring of Fig. 2.

Figure 4 is a perspective view of one of the similar clip devices.

Figure 5 is a broken view in vertical sectional elevation of a portion of the furnace structure showing a modification of the outer portion of the hearth and the igniter means.

Figure 6 is a broken face view of the ring of Fig. 2.

Figures 7 and 8 are broken face views of modifications of the ring structure; and

Figure 9, a section taken at the line 9 on Fig. 8 and viewed in the direction of the arrow.

Referring to the particular construction shown, 10 represents a furnace, shown as of the hot-water-boiler type, having a combustion chamber 11 formed with a hearth portion of refractory material centrally apertured and supported 40 on a centrally apertured plate 12, as for example of metal, carried by the base 13 of the furnace.

The hearth portion shown and formed of any suitable refractory material, comprises a ring-like base portion 14 positioned flatwise on the plate 12, an upstanding ring portion 15 resting at its lower end on the plate 12 and surrounding the ring 14, and a ring portion 16 positioned flatwise on the ring 14, but of smaller diameter 50 than the latter to provide an annular space between the ring 16 and the ring 15.

It may be here said that in the assembling of the parts of the combustion apparatus the oil burner assembly hereinafter referred to is positioned at the lower end of the combustion cham-

ber 11 and the plate 12 then applied to the position shown and the ring portions 14 and 15 cast in place, either at the same time or separately, in which latter case the portion last to be cast is cast before the other sets; in either case the base with its flange forming a monolithic structure. Cement to form the ring 16 is then cast on the base portion 14.

Closely surrounding the hearth ring 16 and extending above this ring and into the space 10 between this ring and the ring 15, is a ring 18 formed of heat resisting metal, as for example and preferably, chromium steel, the ring 18 being preferably about .035 inch in thickness, and forming with the hearth portion 15 an annular space 15 17 about one inch in width.

The ring 18 is shown as held in place by means of inner and outer series of clips 19 and 20, respectively, each of which is of general U-shape as shown in Fig. 4 presenting a base portion 21 and upstanding legs 22 and 23, the latter being formed at its outer side with a downturned tongue 24 spaced therefrom. The clips 19 and 20 are interlocked at their tongues 24 with the ring at openings 25 in the lower edge portion of the 25 latter as shown in Fig. 1, the clips 19 being embedded in the hearth ring 16, and preferably applied with the clips 20 and the ring 18 to the hearth ring 14 to the position shown before the cement forming the hearth portion 16 is filled in. 30 The clips 20, which are located in the space 17, serve to properly position the ring 18 relative to the hearth portion 15 in the assembling of the ring 18 with the base portion 14.

In accordance with my invention the portion of 35 the ring 18 which extends above the hearth section 16 is provided throughout its circumference with openings for the purpose hereinafter described. These openings may be of various shapes and arrangements. Preferably they are 40 provided as shown in Figs. 1 to 6, inclusive, wherein in five circumferential upper rows of circular closely spaced openings 26 and two lower circumferential rows of relatively larger circular closely spaced openings 27 are provided. By way of example and preferably, the openings 26 are $\frac{9}{16}$ inch in diameter and the openings 27 are $\frac{3}{16}$ inch in diameter, adjacent ones of the several rows of openings being spaced closely together, with the uppermost row of openings 26 closely adjacent 45 the upper edge of the ring and the lower row of openings 27 closely adjacent the upper surface of the hearth portion 16, the several rows of openings 26 and 27 extending entirely around the circumference of the ring 18.

Fig. 7 illustrates another arrangement of openings in the ring 18, in accordance with which the upper portion of the ring 18 is provided with a circumferential series of substantially vertical closely spaced slots 28 which by way of example may be $\frac{1}{16}$ inch wide and $\frac{3}{4}$ inch long and below these slots are three circumferential rows of closely spaced openings the upper and lower ones of which are represented at 29 being, by way of example, $\frac{9}{64}$ inch in diameter and the intermediate row of openings represented at 30 of $\frac{3}{16}$ inch in diameter, the lower row of openings 29 extending close to the upper surface of the hearth portion 16.

Fig. 8 illustrates still another modification of the openings in the ring 18. In this arrangement the upper edge portion of the ring is provided with a circumferential series of vertical closely spaced slots 31 preferably about $\frac{3}{8}$ inch in width and louvered on the outer circumference of the ring, as represented at 32. Below the openings 31 are three circumferential rows of closely spaced openings 33, by way of example, $\frac{9}{64}$ inch in diameter, the openings 33 of adjacent rows being closely spaced and the lower row extending close to the upper surface of the hearth portion 16.

The construction shown also comprises an oil burner assembly at the central opening in the hearth for projecting radially outwardly and against the ring member 18, atomized oil for the combustion thereof, adjacent the side wall of the combustion chamber as hereinafter described, the flame produced being in the form of a ring.

Any suitable construction of oil burner assembly may be utilized with the hearth as for example the one shown, which, however, need not be described in detail as it forms no part of the present invention and is fully illustrated and described in the pending application for U. S. Patent filed by Stanley Perry and myself, Serial No. 654,356, filed January 30, 1933, it being sufficient to state that the burner assembly shown comprises a rotary internal-fan-equipped member 34 driven by a motor 35 and containing an annular series of vertical openings 36 through which air is forced radially outwardly, together with a series of radially disposed pipes 37 located at certain of the openings 36 and opening at their inner ends through the side wall of a rotary oil cup 38 likewise driven by the motor 35 and through which pipes the oil discharges by centrifugal force, against the ring 18, the burner assembly being so positioned relative to the hearth portion 16 and the ring 18 that the oil and air discharge in a plane above the hearth portion 16 and the oil discharges from the pipes 37 substantially in the plane of the lower row of openings 26 of Fig. 6, the upper row of openings 29 of Fig. 7 or the upper row of openings 33 of Fig. 8.

The structure shown also comprises (Fig. 1) an ignition device for starting the burner into operation, the particular construction shown being the same as that shown and described in the above referred to pending application, this construction involving, generally stated, a constantly-burning pilot 38 extending upwardly into the space 17 and having an outlet 39 extending crosswise of this space to ignite a stream of gas discharged from a flare-jet burner (not shown) in the space 17 to the rear of the pilot 38 in Fig. 1, tangentially of this space and across the jet of flame from pilot 38.

The gas is supplied to the constantly-burning pilot 38 and the flare-jet-burner through pipes 40

and 41, respectively, communicating with a gas-service pipe 42 through mechanism represented generally at 43 and operating to control the supplying of gas to the flare-jet-burner.

The following is a description of the operation of the combustion apparatus. The oil and air are discharged in a general horizontal direction from the oil and air distributing means of the burner above described, the oil discharging therefrom in atomized condition. The particles of atomized oil being of considerable weight tend to travel outwardly in a substantially horizontal direction, striking the ring 18 which in effect constitutes a primary impact surface, portions of the oil passing through the openings in the ring 18. Assuming the igniter device to have been started in operation, the pilot flame produced thereby ignites the oil discharged through the openings in the ring 18 and also the oil adhering to the surface of this ring and within a few seconds the oil is ignited around the entire periphery of the ring, whereupon the ring 18 quickly becomes heated to an oil-vaporizing temperature with the result that the particles of oil thrown out by the distributor are not only further atomized by impact with the ring, but are completely vaporized.

The construction is such that there is a tendency for a small percentage only of the air discharged from the distributor head to be forced through the openings in the ring 18, the remainder of the air passing upwardly along the inner surface of the ring and rolling outwardly over the top thereof, a cushion of air being produced along the inner surface of the ring 18. In the case of the oil, however, the action is quite different. The oil travels directly outwardly until it strikes the inner surface of the ring 18 where it is further atomized and vaporized, assuming the ring 18 to have been heated by the igniter means as above described; and due to the fact that the oil is vaporized directly on the surface of the ring 18 a large proportion of the oil vapor thus produced passes through the openings in the ring while only a small proportion thereof follows up the inner surface of the ring 18.

The air that passes through the openings in the ring 18 and expands as it leaves these openings quite possibly carries with it a portion, probably a large percentage, of the oil vapor produced, causing a very thorough mixture of the oil and vapor and a portion of the combustion air at this point. While particles of oil thrown directly through the openings in the ring would likely, before becoming vaporized, strike the inner surface of the wall portion 15 which forms a secondary impact surface particularly when the burner is cold, such particles would become thoroughly vaporized and mixed with air and vaporized oil passing through the openings in the ring 18 after the burner becomes heated.

The result of the filtering action by the foraminated ring 18 is to produce in the annular space 17 a mixture of oil and air which is relatively rich in oil vapor but contains insufficient air for complete combustion. Partial combustion results, however, in the space 17 but at a gradually increasing rate as the mixture travels upward in this zone inasmuch as most of the oil vapor passes through the lower perforations in the ring 18 and the percentage of air supplied to this space gradually increases due to the progressive increase of the rate of flow of the air through the upper perforations. Thus the oil vapor may be quickly consumed as it rises from this space of partial combustion and mingles with

the air which rolls outwardly over the upper edge of the ring 18. Consequently there is little, if any, visible flame at the bottom of this space which constitutes a zone of partial combustion.

5 An advantage of the construction is that distinct separation is produced between the zone of combustion and the zone of non-combustion. No combustion occurs in the space between distributor head and the ring 18. There is partial combustion in the space between the ring 18 and the outside refractory, secondary-impact-surface-forming, portion 15 and an intensely hot, but quiet, combustion directly above the space just referred to, the ring 18 thus in effect dividing the combustion chamber into three distinct zones.

Another advantage resulting from the use of the foraminated ring 18 is that the mixture of oil and air in passing through the openings in the ring loses velocity due to expansion of the air and therefore permits the mixture to be more readily ignited.

As will be readily understood, the provision of the louvers 32 in the case of the modification of the ring 18 as shown in Fig. 8 causes the air and oil to discharge through the openings 13 in a tangential direction thereby tending to rotate the mixture and oil vapor beyond the ring which in some cases may be of advantage.

30 While the bottom of the space 17 is shown as disposed at a lower elevation than the upper surface of the hearth portion 16, this is not essential to my invention, and as an example of a modification thereof reference is made to Fig. 5 wherein the space between the ring 18 and the hearth portion 15 is filled up to the level of the upper surface of the hearth portion 16, by a ring 19^a of refractory material, in which case the constantly-burning pilot 38 and the flare-jet-burner 40 above referred to are vertically elongated, as to cause their discharge orifices to extend above the upper surface of the ring 19^a.

While I have illustrated and described certain constructions embodying my invention, I do not wish to be understood as intending to limit it thereto as the same may be variously modified and altered and the invention embodied in other forms of structure, without departing from the spirit thereof.

50 What I claim as new, and desire to secure by Letters Patent, is:

1. In oil combustion apparatus, the combination of a combustion chamber having a hearth and a surrounding side wall extending above said hearth, a ring of heat resisting material rising from the hearth and spaced from the surrounding side wall of said chamber, said ring having openings therethrough, and means at the center of the hearth for projecting air and finely divided oil directly against said ring, said openings extending over substantially the entire area of the portion of the ring impacted by the atomized oil.

2. In oil combustion apparatus, the combination of a combustion chamber having a hearth and a surrounding side wall extending above said hearth, a ring of heat resisting material extending above the upper surface of the hearth and spaced from the surrounding side wall of the chamber, said ring having openings therethrough disposed at different elevations and spaced apart about the circumference of the ring, and means at the center of the hearth for projecting air and finely divided oil directly against said ring, said openings extending over substantially the

entire area of the portion of the ring impacted by the atomized oil.

3. In oil combustion apparatus, the combination of a combustion chamber having a hearth and a surrounding side wall extending above said hearth, a ring of heat resisting material extending above the upper surface of the hearth and spaced from the surrounding side wall of the chamber, said ring having openings therethrough disposed at different elevations and spaced apart throughout the circumference of the ring, and means at the center of the hearth for projecting air and finely divided oil directly against said ring, said openings being distributed throughout substantially the full area of the ring. 15

4. In oil combustion apparatus, the combination of a combustion chamber having a hearth of substantially flat construction with a side wall extending upwardly from the periphery thereof, a substantially vertical perforated wall structure 20 extending above the upper surface of the hearth and spaced from said side wall, said perforated wall structure having its openings spaced at different elevations throughout its height and at close intervals throughout its length, and means 25 at the center of the hearth for projecting air and finely divided oil directly against said perforated wall structure, said perforated wall structure being of sufficient height to intercept substantially all of the projected air and oil. 30

5. In oil combustion apparatus, the combination of a combustion chamber having a hearth of substantially flat construction with a side wall extending upwardly from the periphery thereof, a substantially vertical perforated wall structure 35 extending above the upper surface of the hearth and spaced from said side wall, said perforated wall structure having its openings spaced at different elevations throughout its height and at close intervals throughout its length, and means 40 at the center of the hearth for projecting air and finely divided oil directly against said perforated wall structure, said perforated wall structure being of sufficient height to intercept substantially all of the projected air and oil and serving to permit the passage through the perforations of substantially all of the oil vapors produced from the finely divided oil impacting against it while offering substantial resistance to the passage of air therethrough. 50

6. In oil combustion apparatus, the combination of a combustion chamber having a hearth and a surrounding side wall extending above said hearth, a ring of heat resisting material rising from the hearth and spaced from the surrounding side wall of said chamber, said ring having openings, means for spacing said ring from said side wall and anchoring said ring in position, and means at the center of the hearth for projecting air and finely divided oil directly against said ring. 55

7. In oil combustion apparatus, the combination of a combustion chamber having a hearth and a surrounding side wall extending above said hearth, a ring of heat resisting material extending above the upper surface of the hearth and spaced from the surrounding side wall of said chamber, said ring having openings therethrough disposed at different elevations above said hearth, and means at the center of the hearth for projecting air and finely divided oil directly against said ring, the entire area of the portion of the ring which is impacted by the atomized oil having openings therethrough. 70

8. In oil combustion apparatus, the combina- 75

tion of a combustion chamber having a hearth and a surrounding side wall extending above said hearth, a ring of heat resisting material extending above the upper surface of the hearth and spaced from the surrounding side wall of said chamber, and means at the center of the hearth for projecting air and finely divided oil against said ring, said ring extending across the zone of projection of the oil and having openings of such size and arrangement as to permit of the passage therethrough of a large proportion of the oil in liquid or vapor form, but only a relatively small proportion of the air which impacts said ring.

15. 9. In oil combustion apparatus, the combination of a combustion chamber having a hearth and a surrounding side wall extending above said hearth, a ring of heat resisting material extending above the upper surface of the hearth and spaced from the surrounding side wall of said chamber, said ring having openings disposed at different elevations above said hearth, the openings of a row of lower elevation being of larger size than the openings immediately thereabove, 20 and means at the center of the hearth for projecting air and finely divided oil directly against a portion of said ring having openings therethrough.

10. The combination of a combustion chamber 30 having a hearth and a surrounding side wall extending above said hearth, a ring of heat resisting material extending above the upper surface of the hearth and spaced from the surrounding side wall of said chamber, said ring having at least four rows of openings at different elevations above the hearth, the openings of the two lower rows being of larger size than the openings of the rows thereabove, and means at the center of the 35 hearth for projecting air and finely divided oil directly against a portion of said ring having openings therethrough.

11. In oil combustion apparatus, the combination of a combustion chamber having a hearth and a surrounding side wall extending above the hearth, a ring of heat resisting material extending above the upper surface of the hearth and spaced from the surrounding side wall of said chamber, said ring having openings at different elevations above the hearth and certain of which 45 are in the form of slots, and means at the center of the hearth for projecting air and finely divided oil directly against a portion of said ring having openings therethrough.

12. In oil combustion apparatus, the combination 50 of a combustion chamber having a hearth and a surrounding side wall extending above said hearth, a ring of heat resisting material extending above the upper surface of the hearth and spaced from the surrounding side wall of said chamber, said ring having openings at different elevations above the hearth and the upper ones of which are in the form of slots, and means at the center of the hearth for projecting air and finely divided oil directly against a portion of said ring having openings therethrough.

13. In oil combustion apparatus, the combina-

tion of a combustion chamber having a hearth and a surrounding side wall extending above said hearth, a ring of heat resisting material extending above the upper surface of the hearth and spaced from the surrounding side wall of said chamber, said ring having openings at different elevations above the hearth and the upper ones of which are in the form of slots and the lower ones of which are of substantially circular shape, and means at the center of the hearth for projecting air and finely divided oil directly against a portion of said ring having openings therethrough.

14. In oil combustion apparatus, the combination of a combustion chamber having a hearth 15 and a surrounding side wall extending above said hearth, a ring of heat resisting material extending above the upper surface of the hearth and spaced from the surrounding side wall of said chamber, said ring having openings at different 20 elevations above the hearth, certain of said openings being in the form of slots having louvers at the outer surface of the ring, and means at the center of the hearth for projecting air and finely divided oil directly against a portion of said ring 25 having openings therethrough.

15. In oil combustion apparatus, the combination of a combustion chamber having a hearth and a surrounding side wall extending above said hearth, a ring of heat resisting material extending above the upper surface of the hearth and spaced from the surrounding side wall of the chamber, said ring having openings at different elevations above the hearth, the upper ones of said openings being in the form of slots and the 35 lower ones of substantially circular shape and substantially uniform in size, and means at the center of the hearth for projecting air and finely divided oil directly against a portion of said ring having openings therethrough.

16. In oil combustion apparatus, the combination of a combustion chamber having a hearth and a surrounding side wall extending above said hearth, a ring of heat resisting material extending above the upper surface of the hearth and 45 spaced from the surrounding side wall of said chamber, and means at the center of the hearth for projecting air and finely divided oil directly against said ring, said ring having openings at different elevations above the hearth, certain of 50 said openings being disposed over substantially the entire area of the portion of the ring impacted by the atomized oil and other openings below said portion.

17. In oil combustion apparatus, the combination of a combustion chamber having a hearth and a surrounding side wall extending above said hearth, a ring of heat resisting material extending above the upper surface of the hearth and spaced from the surrounding wall of said 60 chamber and means at the center of the hearth for projecting air and finely divided oil directly against said ring, said ring having openings disposed at, above, and below, the portion of the ring impacted by the atomized oil.

OSCAR C. SCHROEDER.
